(57) **CLAIM**

The ornamental design for a handle for nail polish applicator, as shown and described.

DESCRIPTION

FIG. 1 is a perspective top view of a handle for nail polish applicator embodying the new design;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom thereof; and,

FIG. 8 is a perspective exploded view thereof showing the cap removed from the rest of the handle for nail polish applicator.

Broken lines are used to illustrate portions of the handle for nail polish applicator that form no part of the claimed design.

1 Claim, 8 Drawing Sheets(56)
